UNITED STATES PATENT OFFICE.

LUDOLF FROTSCHER, OF ZITTAU, GERMANY.

APPARATUS FOR DYEING, &c.

SPECIFICATION forming part of Letters Patent No. 552,638, dated January 7, 1896.

Application filed February 28, 1895. Serial No. 540,120. (No model.) Patented in Germany August 9, 1893, No. 74,934; in Austria March 31, 1894, No. 58,754, and in Hungary March 31, 1894, No. 94,751.

To all whom it may concern:

Be it known that I, LUDOLF FROTSCHER, a subject of the King of Saxony, and a resident of the city of Zittau, in the Kingdom of Saxony, Germany, have invented certain new and useful Apparatus for the Treatment of Spun or Woven Fibrous Materials with Dyeing, Washing, Bleaching, Mordanting, and other Liquids or Solutions, (for which I have obtained a patent in Germany No. 74,934, dated August 9, 1893; in Austria No. 58,754, dated March 31, 1894, and in Hungary No. 94,751, dated March 31, 1894;) and I do hereby declare that the following is a full, clear, and exact description of the invention, which will enable others skilled in the art to which it appertains to make and use the same.

My invention relates to an apparatus for the treatment of spun or woven fibrous materials with dyeing, washing, bleaching, mordanting, and other liquids or solutions; and the object of my invention is, first, to provide means for forcing or drawing liquids, atmospheric air, or steam, as may be required, through the fibrous material by placing a liquid container in communication through pipes either with a vacuum-forming apparatus, or a compressed air-vessel, or a steam-generator; secondly, to perform the dyeing process in such a way that the material under treatment is dyed equably throughout, which end is obtained by forcing and drawing through the material the dyeing liquid in a state of equal strength or concentration, not only from the outside thereof inward, but also in the contrary direction from the inside thereof outward; thirdly, to treat the fibrous material with different liquids or solutions one after another by drawing first one liquid from a trough or tank through the material into the liquid-container and discharging it and then drawing another liquid from another trough or vessel into the liquid-container, from which said liquid is forced through the material into the first-mentioned trough or tank.

I attain the above object by means of the apparatus shown in the accompanying drawings, in which—

Figure 1 is a part sectional front elevation thereof; Fig. 2, a part sectional side eleva-

tion. Fig. 3 is a detail view, on an enlarged scale, showing the manner in which cop-spindles may be fixed on a material-carrier; and Fig. 4, a detail view, on an enlarged scale, of a material-carrier with woven goods wound thereon.

d is a liquid or solution container which is in connection by a valve *m* and pipe *m'* with a vacuum apparatus *b*, and by a valve *n* and pipe *n'* with a compressed-air reservoir (compressor) *c*.

a is an air-pump; *e*, Fig. 2, a vessel for supplying through pipe *i* and valve *s* auxiliary or additional liquid to the liquid-container *d*; *o*, a steam-pipe fitted with a valve *o'*.

f is an open trough or tank.

g is a hollow cylinder, which is suspended in the trough *f* and serves for the reception of the goods to be treated. Said cylinder, which is mounted so as to be readily removable, consists, according to the nature of the goods to be treated, of a perforated hollow warp-beam, Fig. 4, upon which all kinds of spun or woven goods may be wound, or of a pipe in which perforated hollow spindles for the reception of cop-bobbins, Fig. 3, are so fixed that the interior of the spindles is in communication with the inside of the pipe *g*. The inside of the material-carrier is in communication with the liquid-container *d* through stuffing-box jointed-pipe connections *p*.

h are disks mounted upon the ends of the material-carrier *g* and serving as wheels for moving the latter to and from the trough, and also protect the cop-spindles from injury when this movement is being effected.

In commencing operations the material-carrier *g*, with the goods to be treated upon it, is placed in the dotted-line position *g'*, Fig. 2. The air is withdrawn from it by opening the valves *m* and *q*, and then, after closing valve *m*, steamed through by opening valve *k* in a pipe *k'*, which connects the liquid-container *d* with a steam-generator, the steam passing through the container *d*, pipes *p*, and the material-carrier. The latter is then lowered upon its stuffing-box joints *p'* into the trough *f* and charged with a liquid or solution while the container *d* contains air only. The valve *m* in the pipe *m'* leading to the vacuum apparatus is then opened and the

air withdrawn from the container *d*, pipes *p*, and carrier *g*, in consequence of which liquid is drawn from the trough through the material to the carrier and thence through the 5 jointed pipes *p* into the container *d*. In order to force the liquid back again into the trough *f* valve *m* is closed, and according as the process is to be a cold or a hot one either valve *n* in the pipe leading to the compressor 10 or *e* is opened to admit compressed air, or valve *k* in the pipe leading to the steam-generator opened to admit steam, so that the liquid is driven from the container *d* and forced through the material under treatment in a 15 contrary direction—that is, from the inside to the outside. This operation may be repeated several times until the material has been sufficiently treated with the liquid. In the use, for instance, of a dyeing liquid or 20 solution the material does not in the just-described process take up the dye equally throughout, as in the suction of the dyeing liquid through the material to the container *d* the outer portion of the fibers or threads 25 first takes up the dye-stuff, and therefore the inner portion is dyed a lighter color, and when the dyeing liquid is forced back again it is not of sufficient strength or concentration for dyeing purposes. In order to 30 avoid this disadvantage and to be able to dye the material equally throughout an auxiliary liquid or solution is supplied to the vessel *e* which is in connection with the container *d*, and when an addition of fresh dyeing liquid is considered to be necessary the 35 valves *m* and *s* are opened, whereupon the auxiliary liquid is drawn from the vessel *e* into the container *d*, where by the action of steam supplied through pipe *o* it is inti- 40 mately mixed with the previously-used dyeing liquid present therein. The liquid thus strengthened or resaturated is, in the manner above described, forced back again through the material into the trough *f*, the inner por- 45 tion of the goods or fibers then being the first to take up the dye. After the dyestuff has been drawn and forced back several times in this way the material will be found to be dyed regularly throughout. The material- 50 carrier *g* is then raised from the trough *f* by turning it with the pipe connections on the stuffing-box joints *p* into the position *g'*, and the material thereon may be at once, for the purpose of drying or oxidizing it, subjected 55 to a vacuum or to steam or atmospheric air pressure, as hereinbefore described.

Therefore in using this apparatus saturated dyeing liquid is first drawn through the goods from the outside to the inside and then 60 again also saturated dyeing liquid forced through the goods from the inside to the outside, so that in the latter case the dye comes in contact with the inner portion of the same, which in the dyeing process is a very important advantage. Further by means of the 65 apparatus the material may be treated with

two different liquids at one operation. The process is then as follows: The carrier *g*, with the material to be treated upon it, is lowered into the trough *f*, and then, after opening the 70 valve *q*, the container *d*, by opening valve *m*, placed in communication with vacuum apparatus *b*, whereby the air is exhausted from the container *d* and the pipe connections *p* and liquid drawn from the trough *f* through the 75 material from the outside thereof into the container *d*. When the material has been sufficiently treated in this way, valve *q* is closed and the liquid discharged from the container *d* past valve *t* into a suitable vessel placed 80 underneath. The second liquid or solution is then, after opening the valves *m* and *s*, drawn by suction or vacuum from the vessel *e* into the container *d*, and this latter then placed in communication with the compressor 85 or with the steam-generator either by opening valve *n* or valve *k*, as the case may be, whereby the liquid in the container *d* is, after opening valve *q* and closing valve *t*, forced by compressed air or by steam through the pipe connec- 90 tions *p*, the carrier *g*, and from the inside to the outside of the material into the trough *f*. In like manner a different kind of liquid, a tannic-acid solution, for instance, may be supplied to the trough *f*, drawn through the 95 material into the container *d* and discharged therefrom, then by means of a vacuum the container supplied from vessel *e* with a mordanting liquid to be forced through the material to the trough *f*, so that the material may 100 be treated with two different liquids, one immediately after the other, the one being drawn from *f* to *d* and the other forced from *d* to *f*.

What I claim as my invention, and desire to secure by Letters Patent, is—

105

1. An apparatus for the treatment of spun or woven fibrous materials with liquids or solutions, comprising a perforated hollow carrier *g* upon which the goods to be treated are wound or placed, said carrier being readily 110 raised from, and lowered into a trough *f* by means of jointed pipe connections *p*; and a liquid container *d* which is connected with the carrier *g* through said pipe connections, with a vacuum apparatus *b* through pipe *m'* 115 and valve *m*, with a compressed air reservoir *c* through pipe *n'* and valve *n* and with pipe *k'* and valve *k* adapted to connect with a steam supply, for the purpose specified, substantially as described and shown.

120

2. An apparatus for the treatment of spun or woven fibrous materials with liquids or solutions, comprising a perforated hollow carrier *g* upon which the goods to be treated are wound or placed, said carrier being readily 125 raised from, and lowered into a trough *f* by means of jointed pipe connections *p*; a liquid container *d* which is connected with the carrier *g* through said pipe connections, with a vacuum apparatus *b* through pipe *m'* and 130 valve *m*, with a compressed air reservoir *c* through pipe *n'* and valve *n* and with pipe *k'*

and valve *k* adapted to connect with a steam supply; and in connection with the container *d*, a vessel *e* adapted to receive an additional or auxiliary liquid or solution or a different liquid or solution, for the purpose specified substantially as described and shown.

5 In testimony whereof I sign this specifica-

tion in the presence of two subscribing witnesses.

L. FROTSCHER.
